UNITED STATES PATENT OFFICE.

WOLF T. GOLDSMITH, OF NEWARK, NEW JERSEY.

DESIGN FOR A BAG FRAME.

Application filed December 11, 1925. Serial No. 15,718. Term of patent 3½ years.

To all whom it may concern:

Be it known that I, WOLF T. GOLDSMITH, a citizen of the United States, and a resident of Newark, in the county of Essex and State of New Jersey, have invented a new, original, and ornamental Design for Bag Frame, of which the following is a specification, reference being had to the accompanying drawing, forming part thereof.

I claim:

The ornamental design for a bag frame, as shown.

WOLF T. GOLDSMITH.
